MINING MACHINE TRANSPORT MEANS

William W. Dartnell, Claremont, N. H., assignor
to Sullivan Machinery Company, a corpora-
tion of Massachusetts

Application August 23, 1937, Serial No. 160,378

13 Claims. (Cl. 262—30)

This invention relates to mining machines, and more particularly, but not exclusively, to improvements in the transport means for a coal mining machine of the flexibly fed, floor cutter type whereby the machine may be transported from one working place to another about the mine. In coal mines of a certain character, it is undesirable to lay a trackway and install trolley power lines in the mine passages, and therefore it is necessary to employ readily portable transport means for the coal mining equipment which may run directly along the mine floor on its own traction wheels without the necessity of a trackway. It has been found that pneumatic tires, such as those used on automobiles, are well adapted to use under such conditions since they provide not only adequate traction, but also provide cushioned movement of the mining machine over an uneven mine floor.

An object of this invention is to provide an improved transport means for a coal mining machine. Another object is to provide an improved mining machine transport means which is driven from the feeding mechanism of the mining machine, thereby simplifying the propelling mechanism for the transport means. A further object is to provide an improved transport means for a coal mining machine of the flexibly fed, floor cutter type wherein the transport means is driven through elements of the flexible feeding mechanism. Yet another object is to provide, in a machine of the above character, improved transport means wherein the traction means therefor are connected to and driven directly by the feed operating and controlling members of the machine feeding mechanism. A still further object is to provide an improved transport means for a coal mining machine including transport wheels attachable to the machine whereby the machine may be moved from place to place about the mine without the use of a separate transport truck. Still another object is to provide, in a machine of the type having cable winding drums for feeding and guiding the machine during its movement over the mine floor during the cutting operation, improved transport means comprising supporting and driving wheels attachable directly to the cable winding drums of the machine, so that the wheels are driven by the drums, and also embodying a caster wheel attachable to the cutter bar of the machine, or some other suitable point, to facilitate steering of the machine during transport. These and other objects and advantages of the invention will, however, hereinafter more fully appear.

In the accompanying drawings, there are shown for purposes of illustration several forms which the invention may assume in practice.

In these drawings:

Fig. 1 is a top plan view of a coal mining machine having embodied therein one illustrative form of the improved transport means. 5

Fig. 2 is a side elevational view of the mining machine shown in Fig. 1.

Fig. 3 is an enlarged horizontal sectional view 10 taken substantially on line 3—3 of Fig. 2, parts being shown in plan to facilitate illustration.

Fig. 4 is a transverse vertical sectional view 15 taken substantially on line 4—4 of Fig. 3 with the machine resting on the mine floor and the traction wheel detached from the cable winding drum.

Fig. 5 is a detail view illustrating a portion of the feed gearing.

Fig. 6 is a view similar to Fig. 2, on a reduced scale, showing the front caster wheel connected 20 to the cutter bar at a different location.

Fig. 7 is a plan view of the mining machine shown in Fig. 1, with the transport wheels detached from the machine and the feeding and controlling cables extended in operative feeding 25 and controlling relation with respect to the cable winding drums.

Fig. 8 is a view similar to Fig. 1, showing a modified form of construction.

Fig. 9 is a side elevational view of the mining 30 machine shown in Fig. 8.

Fig. 10 is a detail vertical sectional view taken substantially on line 10—10 of Fig. 8.

Fig. 11 is a view similar to Fig. 8, showing still another modified form of construction. 35

Fig. 12 is a side elevational view of the mining machine shown in Fig. 11.

In the illustrative embodiment of the invention shown in Figs. 1 to 7, inclusive, the coal mining machine is generally designated by the reference character 1, and the improved transport means is generally designated 2. The mining machine is herein of the flexibly fed, low vein, floor cutter type, and may be of the same general construction as that disclosed in Figs. 1 to 10, inclusive, in the drawings of a copending application of Joseph F. Joy and Leon E. Simmons, Serial No. 71,653, filed March 30, 1936, now matured into Patent No. 2,131,178, dated September 27, 1938, although it will be evident that the improved transport means may be associated with coal mining machines of various other types. 45

The mining machine 1 comprises a machine frame 3 having a smooth bottom surface 4 adapted to rest upon the mine floor for supporting the 50

55

machine for sliding movement over the mine floor during the cutting operation and maneuvering of the machine with respect to the coal face. Supported by the machine frame and projecting forwardly therefrom is an elongated plane cutter bar 5 having guided for circulation about its margin an endless cutter chain 6. Mounted on the rearward portion of the machine frame and arranged at opposite sides of the machine on aligned horizontal axes extending transversely of the machine, are feed operating and controlling members 7 and 8, herein in the form of cable winding drums having feeding and controlling cables 9 and 10 respectively wound thereon. Supported within the machine frame is a reversible motor having its power shaft 11 operatively connected to the driving means for the cutter chain and the cable winding drums. When the transport means is detached from the machine in a manner to be later explained, the machine rests on its own bottom directly on the mine floor, as shown in Fig. 7; and arranged at the rear end of the machine are sets of guide sheaves 12 and 13, while located at the front end of the machine is a front guide sheave 14, and the feeding and controlling cables 9 and 10 are adapted to be extended from their drums in various manners about these guide sheaves to effect maneuvering of the machine and feeding of the machine during the cutting operation, in the manners well understood by those skilled in the art.

The driving mechanism for the cable winding drums may be similar to that described in the above mentioned Joy and Simmons application, with the exception that, in this instance, the driving gearing for the drums is so constructed as to effect drum rotation in the same direction. Formed on the rear end of the motor power shaft 11, as shown in Fig. 3, is a spur pinion 15 meshing with spur gears 16 and 17 arranged on parallel horizontal axes extending longitudinally of the machine and spaced equi-distantly from the central longitudinal vertical plane of the machine, the motor pinion driving the spur gears 16 and 17 in the same direction. The spur gears are formed integral with shafts 18 and 19 respectively, suitably journaled within bearings supported within the machine frame, and these spur gears are connectible by multiple disc clutches 20, 20 to coaxial shafts 21 and 22. Formed on the shaft 19 is a spur gear 23 meshing with a spur gear 24 (see Fig. 5) keyed to a horizontal shaft 25, herein arranged parallel with the shaft 19. The shaft 25 is suitably journaled within the machine frame, and formed integrally with the shaft is a spur gear 26 meshing with a spur gear 27 coaxial with the spur gear 17. Meshing with and driven by the spur gear 27 is an intermediate spur gear 28 meshing with a spur gear 29 coaxial with the spur gear 16. The spur gears 16 and 17 constitute the high speed terminal gears of the high speed transmission, while the spur gears 27 and 29 constitute the low speed terminal gears of the low speed transmission. The gears 27 and 29 are connectible by multiple disc clutches 30, 30 to the shafts 21 and 22, respectively. The sets of clutches 20 and 30 are provided with suitable shipper mechanism 31, 31. Fixed to the shafts 21 and 22 are worms 32 and 33 respectively, herein having teeth of the same pitch and inclination instead of opposite inclination as disclosed in the above mentioned copending application; and these worms each mesh with a worm wheel 34 connectible by a multiple disc clutch 35 to a shaft 36. The shafts 36, 36 are arranged in axial aline-

ment on horizontal axes extending transversely of the machine in parallelism with the cable winding drum axes. Each shaft has formed thereon a spur gear 37 meshing with an internal gear 38 formed on the drum. Each drum is provided with an eccentric mounting 39 having an operating lever 40 whereby the drum may be rotated to bring the internal gear out of mesh with its driving gear, so that the drum may freely rotate. Each drum is journaled on a bearing sleeve 41 supported by the eccentric 39, and the latter in turn is rotatably mounted on and supported by a stub shaft 42 projecting from the side of the machine frame. It will thus be seen that when the internal gears are brought into meshing engagement with their driving gears and the clutches 35 are applied, the cable winding drums may be driven in winding direction at either a high or a low speed under the control of the high and low speed clutches 29 and 30. When the driving motor is reversed, the drums may, of course, be driven at either a high or a low speed in the reverse direction. As a similar feeding mechanism is clearly described in the above mentioned copending application and as the mode of operation of a mining machine of the type disclosed is well known to those skilled in the art, further description of the mining machine structure is considered unnecessary.

Now referring to the improved transport means for the machine, it will be noted that when the machine is resting on its bottom surface on the mine floor, as shown in Fig. 7, and it is desired to transport the machine about the mine, the machine frame is jacked up, in any suitable manner, and supported in its elevated position by suitable blocking. When the machine is in its elevated position, traction wheels, herein of the pneumatic tire type, such as commonly used on automobiles, are attached directly to the cable winding drums 7 and 8. These traction wheels each comprise a large hub 45 having a flange 46 provided with an annular shoulder 47 adapted to surround and engage the exterior periphery of the outer drum flange, in the manner clearly shown in Fig. 3. When the wheel hub is placed in position on the cable winding drum, it is secured in such position by screws 48, in the manner of an automobile wheel mounting. Secured to the wheel hub is a rim 49 adapted to support and retain in position thereon the flanges 50 of a conventional pneumatic tire casing 51. Attached to the forward end of the cutter bar 5 is a bracket 52 secured, as by bolts 53, to the cutter bar and supporting a swivel member 54 of a caster wheel 55, the latter also having a pneumatic tire. When the supporting wheels are properly attached in position on the machine, the machine is again jacked up and the blocking removed from beneath the same, and thereafter the machine is lowered to bring its supporting wheels into engagement with the mine floor. When the machine is so supported, the traction wheels may be driven through the feed driving gearing at either a high or a low speed and in either of opposite directions by the mining machine motor, and as these wheels are driven to propel the machine about the mine, steering of the machine may be facilitated by the front caster wheel. When the traction wheels are secured to the cable winding drums, the cables 9 and 10 wound on the drums are tightly wrapped around the drums and have their free ends suitably fastened so that the cable ends will not be whipped around as the

drums are rotated to effect drive of the traction wheels.

In the arrangement shown in Fig. 6, the caster wheel bracket 52 is detached from the forward end of the cutter bar and the caster wheel swivel 54 is swivelly mounted directly within an opening formed in the cutter bar near the rear end of the latter, so that the caster wheel is brought nearer to the traction wheels, thereby providing a shorter wheel base to facilitate steering of the machine. Otherwise this construction is the same as that above described. The cutter bar may be perforated by a series of longitudinally spaced openings for receiving the caster wheel swivel 54, so that the caster wheel may be located in various positions longitudinally of the cutter bar as desired.

In the modified form of the invention shown in Figs. 8, 9 and 10, the improved transport means is shown associated with a room and pillar mining machine of the standard type as is also clearly described in the above mentioned Patent No. 2,131,178 and disclosed in Figs. 11 to 18 thereof. As in the form of the invention above described, the feed driving gearing is modified so that the cable winding drums are driven in the same direction, instead of in opposite directions as in the above mentioned copending application. The mining machine of this form of the invention comprises a machine frame 60 having mounted within the bottom portion thereof and projecting forwardly from the forward end of the frame, an elongated plane cutter bar 61 having guided for circulation about its margin, an endless cutter chain 62. Mounted on the machine frame above the rearward portion of the cutter bar is a reversible motor 63 having its power shaft connected to the cutter chain and to the cable winding drums 64 and 65. The driving gearing for the cable winding drums is the same as that disclosed above and illustrated in Figs. 3, 4 and 5, and therefore a repetition of the description thereof is considered unnecessary. The improved transport means for the mining machine, in this instance, comprises a pair of traction wheels 66, 66 having conventional pneumatic tires and having their hubs 67 journaled on roller bearings 68 supported by stub shafts 69 projecting laterally from the opposite sides of the machine frame. The axes of the traction wheels are herein arranged parallel with the drum axes in advance of the drums, but below a horizontal plane including the drum axes, as shown in Fig. 9. Formed on the wheel hubs are spur gears 70, 70 meshing with spur gears 71, 71 formed on the inner drum flanges of the cable winding drums 64 and 65 respectively. The traction wheels are secured in position on the stub shafts by nuts 72 threaded on the ends of these stub shafts, and the wheels are provided with usual hub caps 73 for enclosing the internal bearing and nut structure. Attached to the forward end of the cutter bar is a bracket 74 secured, as by screws 75, to the cutter bar and having a swivel 76 and a caster wheel 77, the caster wheel being similar to that disclosed in Fig. 2 of the drawings. When it is desired to transport the mining machine about the mine, the machine is jacked up onto suitable blocking and the traction wheels are attached to the sides of the machine frame and the front caster wheel is attached to the forward end of the cutter bar. The machine is then again jacked up, the blocking removed from beneath the same and then lowered to bring the supporting wheels into engagement with the

mine floor. As in the form of the invention above described, the traction wheels are driven through the feed gearing by the cable winding drums 64 and 65.

In the modified form of the invention shown in Figs. 11 and 12, the mining machine is of the same general room and pillar type as that disclosed in Figs. 8 and 9, except in this instance the cable winding drums 80 and 81 are arranged on aligned horizontal axes extending transversely at the forward end of the machine frame 82. Projecting forwardly from the machine frame is an elongated plane cutter bar 83 having guided for circulation about its margin an endless cutter chain 84, and the cutter chain and the cable winding drums are driven from the motor of the mining machine in substantially the same manner as that described above in the form of the invention disclosed in Figs. 3, 4 and 5. In this form of the invention, the traction wheels 85, 85 are secured directly to the drums 80 and 81, respectively, and are arranged coaxially with the drums at the forward end of the machine frame. Secured at 87 to the rear end of the machine frame is a bracket 88 to which is attached a swivel member 89 of a caster wheel 90. As in the forms of the invention above described, the traction wheels and caster wheel have conventional pneumatic tires. Otherwise this form of the invention is the same as those above described.

In all forms of the invention, the mining machine may be transported over the mine floor by the traction wheels, and steering of the machine during transport is facilitated by the caster wheel. When the working place is reached, the mining machine is jacked up and the traction wheels and the caster wheel are detached from the machine and the machine is thereafter lowered onto its own bottom on the mine floor. When the supporting wheels are detached from the machine, the cables of the cable winding drums are extended around the various guide sheaves on the machine and the machine is maneuvered with respect to the coal face and fed over the mine floor during the cutting operation, in the manners well understood by those skilled in the art. By attaching the supporting wheels directly to the mining machine, the necessity of a separate transport truck is entirely eliminated and the machine is greatly simplified since the drum driving gearing is employed for driving the traction wheels to effect propulsion of the machine about the mine. Also by providing supporting wheels of the type disclosed, the machine may be propelled directly by engagement of the wheels with the mine floor wholly without the use of a trackway. Other uses and advantages of the improved transport means will be clearly apparent to those skilled in the art.

While there are in this application specifically described several forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. The combination with a mining machine of the floor cutter type adapted to slide on its own bottom over a mine floor during the cutting operation and having feed driving gearing, of

- means for transporting the mining machine comprising transport wheels adapted to run directly on the mine floor and attachable directly to parts of the mining machine for supporting the latter with its bottom raised from the mine floor, said wheels having releasable attaching means including cooperating attaching elements on the machine and wheels, and driving connections between certain of said transport wheels and said feed driving gearing for independently driving said wheels and embodying independent control means for said wheels whereby steering of the machine by the wheels during transport may be effected, said wheels being detached from the machine and the latter resting directly on the mine floor during the coal cutting operation of the machine.
2. The combination with a coal cutting machine of the floor cutter type adapted to slide on its own bottom over a mine floor during the cutting operation and having a machine frame and a cutter bar projecting from said frame, of means for transporting the coal cutting machine with its bottom raised from the mine floor comprising traction wheels attachable to said machine frame and adapted to run directly on the mine floor, means deriving its power from the coal cutting machine for independently driving said traction wheels and embodying independent control means for said wheels whereby steering of the machine by the wheels during transport may be effected, a swivelled wheel attachable to said cutter bar, and detachable means for attaching the traction wheels and said swiveled wheel to said machine frame and cutter bar respectively, said wheels being detached from the machine frame and cutter bar and the machine resting directly on the mine floor during the coal cutting operation of the machine.
3. The combination with a coal cutting machine of the floor cutter type adapted to slide on its own bottom over the mine floor during the cutting operation and having a machine frame and a cutter bar projecting from said frame, of means for transporting the coal cutting machine with its bottom raised from the mine floor comprising transport wheels adapted to run directly on the mine floor and attachable directly to said machine frame and to the outer extremity of said cutter bar, detachable means for attaching said transport wheels to the machine frame and cutter bar respectively and including cooperating attaching elements on the wheels and on the frame and cutter bar, said wheels being detached from the machine and cutter bar and the machine resting directly on the mine floor during the coal cutting operation of the machine, and means deriving its power from the coal cutting machine for independently driving certain of said transport wheels and embodying independent control means for the wheels whereby steering of the machine by the wheels during transport may be effected.
4. The combination with a coal cutting machine of the type adapted to rest on its own bottom upon and slide over a mine floor during the cutting operation, of means for transporting the coal cutting machine during movement of the latter about the mine comprising transport wheels adapted to run directly on the mine floor and attachable directly to parts of the coal cutting machine for supporting the latter with its bottom raised from the mine floor, said transport wheels being detached from the coal cutting machine during movement of the machine on its

own bottom over the mine floor during the cutting operation, detachable means for attaching said transport wheels to the coal cutting machine, and means deriving its power from the coal cutting machine for independently driving certain of said transport wheels and embodying independent control means for the wheels whereby steering of the machine by the wheels during transport may be effected. 5

5. In a mining machine transport means, the combination with a mining machine of the floor cutter type adapted to slide on its own bottom over the mine floor during the cutting operation and having feed operating and controlling members for feeding the machine over the mine floor, 15 of transport wheels attachable directly to the machine for supporting the machine with its bottom raised from the mine floor, and means for connecting said transport wheels to said feed operating and controlling members for driving by 20 the latter.

6. In a mining machine transport means, the combination with a mining machine of the floor cutter type having feed operating and controlling members for feeding the machine over the mine 25 floor and for guiding the machine during its movement over the mine floor, of transport wheels attachable to the machine including wheels connected to and respectively driven by said feed operating and controlling members. 30

7. In a mining machine transport means, the combination with a mining machine of the floor cutter type having feed operating and controlling members for feeding the machine over the mine floor and for guiding the machine during 35 its movement over the mine floor, of transport wheels attachable to the machine including wheels connected to and respectively driven by said feed operating and controlling members, and an additional supporting wheel located at 40 a point remote from said transport wheels.

8. In a transport means for mining machines, the combination with a mining machine of the floor cutter type adapted to rest on its own bottom for sliding movement over the mine floor 45 during the cutting operation and having feed operating and controlling members for feeding and guiding the machine over the mine floor and a cutter bar, of transport wheels attachable to the machine for supporting the latter with its 50 bottom raised from the mine floor, and means for connecting certain of said wheels to said feed operating and controlling members respectively for driving by the latter, and another wheel connected to said cutter bar. 55

9. The combination with a mining machine having a machine frame adapted to rest on its own bottom upon and move in any direction over a mine floor and a cutter bar projecting from the machine frame, of means for transporting the mining machine with its bottom raised from the mine floor comprising traction wheels adapted to run directly on the mine floor and attachable directly to the machine frame at one end thereof, means deriving its power from 65 the mining machine for independently driving said traction wheels and embodying independent control means for the wheels whereby steering of the machine by the wheels during transport may be effected, a swiveled caster wheel attachable to said cutter bar at the opposite end of the machine frame, and detachable means for attaching said traction wheels and said caster wheel to the machine frame and cutter bar respectively, said wheels being detached from the 70 75 mine floor during movement of the machine.

machine frame and cutter bar and the machine resting directly on the mine floor during the coal cutting operation of the machine.

10. The combination with a coal cutting machine of the floor cutter type having flexible feeding means including relatively rotatable feed operating and controlling members adapted to cooperate respectively with feeding and controlling elements, of means for transporting the coal cutting machine including traction wheels adapted to run directly on the mine floor and attachable directly to the coal cutting machine and independently driven by said feed operating and controlling members respectively, releasable means for attaching said traction wheels to the machine, and means for connecting said traction wheels in driving relation with said feed operating and controlling members and embodying independent control means for the traction 20 wheels whereby steering of the machine by the wheels during transport may be effected.

11. The combination with a mining machine of the floor cutter type adapted to slide on its own bottom over a mine floor during the cutting 25 operation and having flexible feeding means for feeding the mining machine over the mine floor comprising terminal feeding elements on the machine and driving gearing for said terminal feeding elements, of means for transporting the mining machine comprising traction wheels adapted to run directly on the mine floor and attachable directly to the machine and independently driven by said terminal feeding elements respectively through said feed driving gearing, 30 releasable means for attaching said traction wheels to the machine, and means for connecting said traction wheels in driving relation with said

terminal feeding elements respectively and embodying independent control means for said wheels whereby steering of the machine by said wheels during transport may be effected.

12. In a mining machine transport means, the combination with a mining machine of the floor cutter type adapted to rest on its own bottom upon and slide in any direction over a mine floor during the cutting operation, of means for transporting the mining machine with its bottom raised from the mine floor comprising traction wheels adapted to run directly on the mine floor and attachable directly to the mining machine at one end thereof, means for independently driving said traction wheels and embodying independent control means for said wheels whereby steering of the machine by said wheels during transport may be effected, a swiveled caster wheel attachable to the mining machine at the opposite end thereof, and detachable means for 20 attaching said traction wheels and said caster wheel to the mining machine and including cooperating attaching elements on the machine and wheels, said traction wheels and said caster wheel being detached from the mining machine during 25 movement of the machine on its own bottom over the mine floor during the cutting operation.

13. The combination with a coal cutting machine of the type adapted to rest upon and slide over a mine floor during the cutting operation 30 and having flexible feeding means comprising haulage drums for feeding and guiding the machine, of means for transporting the machine with its bottom raised from the mine floor comprising transport wheels attachable directly to 35 and respectively driven by said haulage drums.

WILLIAM W. DARTNELL.
